Assistant Examiner — Suzanne Tisdell

(57) CLAIM

The ornamental design for jeans with jewelry hoop on hem, as shown and described.

DESCRIPTION

FIG. 1 is a rear perspective view of jeans with jewelry hoop on hem comprising the new design;

FIG. 2 is a front elevational view thereof;

FIG. 3 is a front elevational enlarged view of a portion of FIG. 2;

FIG. 4 is a rear elevational view of the design of FIG. 1; and, FIG. 5 is a rear elevational enlarged view of a portion of FIG. 4.

Broken lines shown in the drawings illustrate portions of the jeans with jewelry hoop on hem that form no part of the claimed design.
